UNITED STATES PATENT OFFICE.

ARTHUR COLLINS, OF WEYBRIDGE, ENGLAND.

STAIRCASE FOR SCENIC EFFECTS.

1,273,383.

Specification of Letters Patent. Patented July 23, 1918.

Application filed October 16, 1917. Serial No. 196,940.

To all whom it may concern:

Be it known that I, ARTHUR COLLINS, managing director, a subject of the King of England, and residing at Weybridge, in 5 the county of Surrey, England, have invented certain new and useful Improvements in Staircases for Scenic Effects, of which the following is a specification.

This invention relates to a spiral staircase for the purpose of producing scenic effects. This staircase is of a transportable nature and is adapted to be locked in position upon a stage. A landing is arranged adjacent to the top of the stairway of the 15 staircase so that artistes can pass from said stairway to the landing or vice versa. The staircase is preferably tapered in height and locked in position by a displaceable member adapted to engage the staircase. This dis- 20 placeable member may be a locking bridge which with advantage forms or supports the landing in the form of a gangway or platform by means of which the artistes can appear from the borders and continue down 25 the staircase to the stage level, or alternatively can ascend from the stage level and disappear behind the borders. If preferred, however, the landing in the form of a platform or gangway may be separate 30 from the locking bridge, but in any case the landing is arranged adjacent to the top of the staircase and concealed from the audience.

The spiral staircase is so arranged as to 35 be revoluble around a longitudinal axis, or with a central column, and for this purpose I support the said column at bottom below the stage, and at top preferably by a displaceable girder (forming the locking 40 bridge) secured to the fly-rail. The lower part of the staircase is provided with wheeled members such as balls or rollers whereby the staircase may be supported upon a correspondingly shaped bracket. 45 With a view to facilitating the travel of the spiral staircase on or across the stage, or from one theater to another, I employ caster wheels, trailing wheels or the like as these bottom supports for the transportable staircase. 50 These caster wheels may be obtained by means of bearings or rollers mounted on swivel arms pivoted to the bottom of the staircase.

The staircase may rotate with the center 55 column in either direction, suitable revers-

ing means being employed. The spiral staircase may be illuminated in any desired manner, and in some forms I may provide balustrades or banisters to the stair case which conceal flags or the like, said flags being adapted to be projected when desired and thereupon floating with the staircase. Where two or more of these revoluble staircases and central columns are employed, they may be arranged to rotate in opposite 60 65 directions.

Upon the accompanying sheet of drawings, Figure 1 is an elevation of the staircase adapted to be revolved. Fig. 2 is a plan view on a larger scale of a suitable 70 driving gear for revolving the staircase. Fig. 3 is a sectional elevation also on a larger scale of a coupling between the central column and the driving gear. Fig. 4 shows a caster roller for the foot of the 75 staircase. Fig. 5 is a diagram showing three staircases with separate drive to each column. Fig. 6 is a diagram of another locking device for the top of the column. Fig. 7 shows a balustrade with flagstaff re- 80 cessed therein. Fig. 8 is a diagram showing duplicate couplings and alternative drives for the staircase.

In these drawings a spiral staircase is shown at 1, having a stairway 2 extending outwardly to balustrades or banisters 3, the said stairway in Fig. 1 extending inwardly to the central column 4. The stairway is thus wound spirally around the central column 4. This column 4 is at top shown 90 secured to a cross girder 5 by a strap or housing 6 which may contain a ball bearing of any suitable type. This girder 5 or bridge is a displaceable member arranged to be lowered on to the column 4 to lock the 95 staircase in position, the housing 6 being appropriately situated to engage the column.

At bottom the central column 4 rests upon a thrust bearing 7 which takes the weight of the column. Below the stage level 8, there is arranged an annular bracket 9 through the center of which shaft 4 passes and may be guided, and upon the periphery 10 of which the staircase is supported by means of ball-bearing rollers 11. This periphery 105 forms an annular pathway for the rollers 11. Any number of these rollers 11 may be employed, arranged at intervals around the base of the staircase. A worm wheel 12 is mounted upon the lower end of column 4, 110

said wheel 12 being engaged and driven by a worm 13 rotated by any suitable source of power. In Figs. 1 and 2, an electric motor 14 is shown for this purpose but any other suitable source of power may be employed.

It will be understood that by means of the worm drive 12-13, the central column 4 will be rotated carrying with it the spiral staircase, and artistes may travel up or down the stairs 2 from one end of the staircase to the other.

A landing such as a platform or gangway is arranged in proximity to the upper part 15 of the staircase. Thus, the girder 5 in addition to locking the staircase in position may be arranged to form a support from which a landing 5' may be suspended (see Fig. 1) so that the artistes ascending the 20 staircase can step from the latter on to said landing 5' after disappearing into or behind the borders B indicated in dotted lines. For this purpose the gangway or platform 5' may be provided with a hand-rail 5^b and 25 is arranged within a suitable distance of the top step of the stairway 2.

The girder 5 is arranged to be lowered into the position in which it engages with the column 4 and locks the staircase in position, by any suitable means. For this purpose the girder may be carried by plunger rods P hydraulically operated and the girder be pivotally linked to flyrails F.

In Fig. 6, I have shown another method 35 of engaging the bridge 5 with the top of the column 4 so as to lock the staircase in position. The bridge is here hinged or pivoted at 5^a to the flyrail F and provided upon its upper surface with the hand-rail 5^b. The 40 bridge is recessed at 5^c to engage the conical top of the column 4. A ball race or similar bearing may be inserted in the conical recess, if desired, to bear upon said conical top. An intermediate landing 5^d is shown at the 45 top of the stairway 2 and adjacent to the gangway afforded by the bridge 5 and its hand-rail 5^b.

Preferably the rollers 11 are of a journal bearing type as shown in Fig. 4. They are 50 there represented on a shaft 15 carried by a fork 16 which is vertically pivoted at 17 to an arm 18 secured to the bottom of the staircase. This fork device will swivel in the manner of a trailing or caster wheel and 55 facilitate the moving of the staircase upon the stage into or out of position, or from one theater to another.

In lieu of the bearings shown for the top and bottom of the central column, other 60 forms of anti-friction bearings may be employed.

I may also interpose a coupling device between the column 4 and the driving gear. Such an arrangement is shown in Fig. 3.

The column 4 is here shown divided as at 4, 65 4' with squared ends 19 19'. The staircase is connected with the upper portion 4 and 19. A sleeve 20, correspondingly shaped interiorly, is arranged to couple the ends 19, 19', normally together. When it is required 70 to disconnect the ends, the sleeve 20 is raised to the position shown in dotted lines so that its lower end is above the squared shaft 4' and maintained in that position by a pin 21 passing through a hole 22 into a corresponding hole 23 in the squared end 19 of shaft 4.

The column 4 and staircase 1 may be driven in any other convenient manner, as 80 from the top of the column 4, which arrangement will be obvious from Fig. 1 or Fig. 8. In order to reverse the direction of rotation of the column and staircase, I may secure to the top of the column 4 a second worm wheel 12' arranged to be driven by a 85 worm 13' in an opposite direction to the first, and provide couplings of the type shown in Fig. 3 at each end of the column 4 so that by engaging one or other coupling the column 4 may be driven in 90 either direction. Such arrangement is represented diagrammatically in Fig. 8.

In Fig. 5 I have shown three staircases 1, 1^a, 1^b, all supported at top by a girder 5 designed to be attached to the usual fly- 95 rail F of the stage and to be raised and lowered by hydraulic means or otherwise: Hydraulic cylinders are indicated at H. Each staircase is separately driven by a worm drive. These three staircases may be driven, 100 for instance, in the same direction, or the outer two may be driven in one direction and the center one in the opposite direction. The girder 5 is secured to the tops of the columns 4 so as to guide and hold them and 105 for this purpose the girder 5 may be provided with three straps 6 and be arranged to be lowered to engage the columns 4 in said straps, when the columns have been brought to the required positions.

Fig. 1 also shows flags or the like 24 on 110 staffs 25 projecting from the exterior of the staircase. For this purpose some of the balustrades 3 may be made hollow or be recessed, as at 25', (see Fig. 7) so that normally the flag and its staff will be housed in the balustrade. Although only the flagstaff is shown, a suitable latching device, as represented in Fig. 7, may be employed to hold the flagstaff and flag in the concealed 115 position. This device consists of a cover piece 26 for the top of the flagstaff 24, the latter being pivoted at bottom as at 27. The cover piece or latch 26 normally prevents the flagstaff from falling out, but by pulling 120 the latch to one side, e. g., by means of a cord 28, the flagstaff will fall forward and outwardly, assisted by centrifugal force as 125

the staircase revolves. The latches 26 may all be connected to a common controlling cord 28 so that all flags will fall forward and be displayed simultaneously.

5 The staircase may be externally illuminated or decorated by means of electric lamps, as shown at 29.

It is to be noted that the displaceable member 5 which engages and locks the top 10 of the staircase does not hinder the rotation of the latter but maintains it upright when in the desired position.

The borders indicated at B may be the usual theatrical drapery and depend over 15 the top of the staircase so as to conceal from the spectators the topmost stairs of the stairway 2 as well as the landing. The artistes are thus enabled to mount the stairway and disappear behind the borders or to 20 appear from the borders and descend the staircase to the stage.

Having thus described my invention, what I claim as such and desire to secure by Letters Patent of the United States of America, 25 is:—

1. A stair case for scenic effects, comprising a spiral stairway, means for supporting said stairway at bottom, said means comprising wheeled members to allow the staircase 30 case to be moved from one position to another, means for engaging and retaining the staircase in the desired position, and a landing adjacent to the top of the stairway so that artistes can pass to or from said 35 staircase and said landing.

2. A staircase for scenic effects, comprising a stairway wound spirally around a vertical axis, said stairway tapering upwardly, means for supporting said stairway at bottom upon a stage, said means allowing the staircase to be moved from one position to another, means for engaging the upper part 40 of the staircase and retaining the same in the desired position, and a landing adjacent to the top of the stairway so that artistes can pass to or from said landing.

3. A staircase for scenic effects, comprising a spirally wound stairway, said stairway 50 tapering upwardly, means for supporting said stairway at bottom upon a stage said means allowing the staircase to be moved from one position to another, means for engaging the upper part of the staircase and retaining the same in the desired position, a landing adjacent to the top of the stairway so that artistes can pass to or from said staircase and said landing, and means 55 for revolving said staircase when in the desired position.

4. The combination in a staircase for scenic effects, of a spiral stairway which is tapered upwardly, revolute members carried by the lower part of said stairway, said

members allowing the staircase to be wheeled 65 from place to place, means for engaging the upper part of the staircase and locking it in position, and a landing adapted to be brought into position adjacent to the top of said stairway. 70

5. The combination in a staircase for scenic effects, of a spiral stairway which is tapered upwardly, revolute members carried by the lower part of said stairway, said members allowing the staircase to be 75 wheeled from place to place, means for engaging the upper part of the staircase and locking it in position, a landing adapted to be brought into position adjacent to the top of said stairway, and means whereby said 80 staircase can be rotated around its longitudinal axis.

6. A staircase for scenic effects, comprising a spiral stairway, wheel members arranged upon the bottom of said staircase so 85 that said staircase can be wheeled from one position to another, a displaceable member adapted to engage the upper part of said staircase and lock it in position, and a landing arranged adjacent to the top of said 90 stairway so that artistes ascending said stairway can step on to said landing.

7. A revolute staircase for scenic effects, comprising in combination a tapering spiral stairway, means for supporting said staircase at bottom and at top, said supporting 95 means at bottom being secured to a stage, means for rotating said staircase, a landing adjacent to the top of said stairway, and means for concealing said landing. 100

8. A staircase for scenic effects, comprising a tapering spiral staircase, the stairs of said staircase forming a continuous flight from bottom to top, means for supporting said staircase at bottom and at top, a landing adjacent to the top of said stairway, and means for concealing said landing, said staircase being provided with means whereby it may be rotated. 105

9. A staircase for scenic effects, comprising in combination a tapering spiral stairway, the stairs of said stairway forming a continuous flight from bottom to top, means for supporting said staircase at bottom and at top, a landing adjacent to the top of said 110 stairway, means for concealing said landing, balustrades to said staircase, and means for rotating said staircase.

10. A staircase for scenic effects, comprising a stairway wound spirally around a vertical axis, wheel members arranged upon the bottom of said staircase so that said staircase can be wheeled from one position to another, a displaceable member adapted to engage the upper part of said staircase and 115 lock it in position, and a landing arranged adjacent to the top of said stairway so that artistes ascending said stairway can step on 120

to said landing, said landing being movable with said displaceable member so as to come into operative position relatively to the stairway when said displaceable member engages the staircase.

11. A staircase for scenic effects, comprising a tapering spiral stairway, balustrades to said stairway, said balustrades being connected together, wheeled members upon the bottom of said staircase so that said staircase can be moved from one position to another, a landing adapted to be brought into proximity to the top of said stairway and means for engaging and guiding the upper part of said staircase.

12. A staircase for scenic effects, comprising a tapering spiral stairway, balustrades to said stairway, said balustrades being connected together, trailing wheel members upon the bottom of said staircase so that said staircase can be moved from one position to another, a landing adapted to be brought into proximity to the top of said stairway and concealed from the spectators, and means for engaging and guiding the upper part of said staircase, said means including a displaceable member.

13. A staircase for scenic effects, comprising a tapering spiral stairway, balustrades to said stairway, said balustrades being connected together, wheeled members upon the bottom of said staircase so that said staircase can be moved from one position to another, a landing adapted to be brought into proximity to the top of said stairway and concealed from the spectators, and means for engaging and guiding the upper part of said staircase, said means including a displaceable member, and means for rotating said staircase about the longitudinal axis of its spiral stairway.

14. A staircase for scenic effects, having means whereby it may be wheeled into position, means whereby it may be locked in position upon a stage, and a landing arranged adjacent to the top of said staircase and concealed from the spectators.

15. A revoluble spiral staircase for scenic effects, having means whereby it may be wheeled into position, means whereby it may be locked in position upon a stage, and a landing arranged adjacent to the top of said staircase and concealed from the spectators, and means whereby said staircase can be rotated.

16. A revoluble, tapering spiral staircase for scenic effects, having means whereby it may be wheeled into position, said means serving also for the rotation of the staircase, means whereby the staircase may be locked in position upon a stage, power-operated means whereby said staircase can be rotated, a landing arranged adjacent to the top of said staircase, and means for con-

cealing said landing from the view of the spectators.

17. A revoluble staircase, comprising a tapering spiral stairway and balustrades, said staircase having means whereby it may be wheeled into position upon a stage, power-operated means for revolving said spiral staircase, means whereby the staircase can be locked in position at top without hindering its rotation, a landing adapted to be brought into proximity to the top of said stairway, and means for concealing from the spectators said landing and the top of said stairway.

18. A revoluble spiral staircase having means whereby it may be wheeled into position while upright, means for engaging and locking said staircase in position without hindering its revolution, a landing adapted to be brought into position in proximity to the top of said staircase so that artistes can step from said staircase to said landing or vice versa, means for concealing from the audience said landing and the top of said staircase, and means for revolving said staircase.

19. A revoluble spiral staircase for scenic effects, comprising an upwardly tapered stairway, means including wheeled members whereby said staircase can be wheeled into the desired position upon a stage, means for revolving said staircase, said last mentioned means utilizing said wheeled members, a displaceable bridge adapted to engage the top of the staircase and lock it in position without hindering its rotation, a fly-rail, said bridge being pivotally secured to said fly-rail, a gangway carried by said bridge which when said bridge engages said staircase, assumes a position adjacent to the top of said staircase, and means for concealing from the spectators said gangway and the top of said staircase.

20. A revoluble spiral staircase for scenic effects, comprising a spiral stairway, a central column around which the stairway is arranged, means whereby said staircase can be wheeled from place to place, means for engaging and locking said column, a landing adjacent to the top of said staircase, means for concealing said landing, and means for rotating said staircase.

21. A revoluble spiral staircase for scenic effects, comprising a tapering spiral stairway, a central vertical column around which the spiral stairway is wound, means for rotating said staircase, wheeled members arranged at the base of said staircase, said wheeled members allowing the staircase to be moved from one position to another and also serving for the rotation of the staircase, means for engaging and locking said column to support and lock the staircase in position, a landing adjacent to

the top of said staircase and means for concealing said landing.

22. A revoluble spiral staircase for scenic effects, comprising a tapering spiral stairway, a central vertical column about which the stairway is arranged, means for rotating said staircase, means for supporting said column at each end, wheeled members arranged at the bottom of said staircase, 10 said wheeled members allowing the staircase to be moved from one position to another and also serving for the rotation of the staircase, means for engaging and locking said column to support and lock the 15 staircase in position, a landing adjacent to the top of said staircase and means for concealing said landing.

23. A revoluble spiral staircase for scenic effects, comprising a tapering spiral stairway, a central upright column about which the stairway is spirally wound, the stairs of said staircase forming a continuous flight from bottom to top and said stair projecting laterally from said upright column, means 25 for rotating said staircase around its central axis, means for supporting said column at each end, wheeled members arranged at the bottom of said staircase, said wheeled members allowing the staircase to be moved from 30 one position to another and also serving for the rotation of the staircase, means for engaging and locking said column to support and lock the staircase in position, a landing adjacent to the top of said staircase and 35 means for concealing from the spectators said landing and the top of said staircase.

24. A revoluble spiral staircase for scenic effects, comprising a tapering spiral stairway, a central column about which the stairway, a central column about which the stairway is arranged, means for rotating said staircase, means for supporting said column at each end, wheeled members arranged at the bottom of said staircase, said wheeled members allowing the staircase to be moved 45 from one position to another and also serving for the rotation of the staircase, means for engaging and locking said column to support and lock the staircase in position, a landing adjacent to the top of said staircase and 50 means for concealing said landing and the top of said staircase, said central column being provided with a worm wheel, a worm engaging said worm wheel and means for driving said worm.

25. A revoluble spiral staircase for scenic effects, comprising a spiral stairway, swiveling wheeled members attached to the bottom of said stairway, said swiveling wheeled members allowing said staircase to 60 be wheeled from one position to another upon a stage, a bracket arranged below the stage and having an annular periphery, said wheeled members adapted also to travel upon said annular periphery when the stair-

case is in operative position, means for engaging the upper part of said staircase, means for revolving said staircase, and a landing arranged in proximity to the top of said stairway with means for concealing from the spectators said top and said landing.

26. A revoluble spiral staircase for scenic effects, comprising a spiral stairway, wheeled members secured to the bottom of said stairway, means for engaging the upper part of the staircase, means for revolving said staircase, a display device carried by said staircase and means for automatically bringing said display devices into operation by the revolution of said staircase, 75 and a landing adjacent to the top of said staircase.

27. A revoluble spiral staircase for scenic effects, comprising a spiral stairway, means for supporting said stairway at top and bottom so as to permit it to be revolved, means for rotating said staircase by power-operated drive, means for disconnecting said staircase from said drive, and a landing adapted to be brought into proximity to the 85 upper part of said stairway.

28. A spiral staircase for scenic effects, comprising a spiral stairway arranged around a central column and revoluble therewith, said column being supported at each 95 end, a coupling interposed in the length of said column, and means for driving said column through said coupling so as to revolve the staircase.

29. A spiral staircase for scenic effects, 100 comprising a spiral stairway arranged about a central column and revoluble therewith, said column being supported at each end, a coupling interposed in the length of said column and means for rotating said column 105 and staircase in one direction through said coupling, a second coupling interposed in the length of the column and means for driving said column and staircase through said second coupling in the direction opposite to 110 the first.

30. A plurality of spiral staircases for scenic effects, comprising spiral stairways each supported upon wheeled members and revoluble around the longitudinal axes of 115 said spiral stairways, and a single locking member adapted to engage each of the said staircases and maintain them in the desired position.

31. A revoluble spiral staircase for scenic 120 effects, said staircase tapering outwardly so as to be narrower at the top than at the bottom and having a continuous flight of stairs from bottom to top, in combination with a landing arranged in proximity to the upper part of said staircase, and borders concealing said landing and the upper part of said staircase.

32. A revolute spiral staircase for scenic effects, comprising a spiral stairway secured to a central column; means for supporting said stairway at bottom upon wheeled members, a landing arranged in proximity to the top of said stairway, and means for engaging the top of said column, said last mentioned means including a bridge pivoted to one of the fly-rails of the stage.
- 10 33. A revolute spiral staircase for scenic effects, comprising a tapering spiral stairway fitted with balustrades, means for supporting said staircase at top and bottom, means for wheeling said staircase into position, means for rotating said staircase in one direction, separate means for rotating said staircase in the other direction, and a landing adapted to be brought into proximity to the upper end of said stairway.
- 15 34. A revolute spiral staircase for scenic

effects, comprising a tapering spiral stairway, a central column to which said stairway is secured, balustrades to said stairway, means for wheeling said staircase in an upright position into place upon a stage, 25 power-operated means for rotating said staircase, means for engaging said column at top so as to maintain the stairway and column in the desired position, said means including a pivoted bridge, and a landing 30 adapted to be brought into proximity to the upper part of said stairway, said landing being carried by said pivoted bridge.

In testimony whereof I have affixed my signature in presence of two witnesses.

ARTHUR COLLINS.
